(57) **CLAIM**

The ornamental design for a needle remover, as shown and described.

DESCRIPTION

FIG. 1 is a top and right side perspective view of the new design for a needle remover;

FIG. 2 is a top and left side perspective view of the new design for a needle remover;

FIG. 3 is a top side perspective view of the new design for a needle remover;

FIG. 4 is a top elevational view of the new design for a needle remover;

FIG. 5 is a side elevational view of the new design for a needle remover;

FIG. 6 is a bottom elevational view of the new design for a needle remover;

FIG. 7 is a bottom and side view of the new design for a needle remover; and,

FIG. 8 is a top side view of the new design for a needle remover with dashed line showing large needle cap in needle remover.

The dashed lines immediately adjacent to the claimed areas in the views represent the boundaries of the claimed design. The dashed lines in the figures illustrate the portions of the design that form no part of the claimed design. None of the broken lines form any part of the claimed design.
